SPARE TIRE JACKET

Charles J. Kammeyer, Concordia, Mo.

Application June 18, 1956, Serial No. 41,957

Term of patent 3½ years

(Cl. D90—20)

FIG. 4

FIG. 2

FIG. 5

FIG. 3

Figure 1 is a front elevation showing a spare tire jacket embodying my new design, with the flap raised;

Figure 2 is a rear elevation of Figure 1, with the flap down;

Figure 3 is a front elevation thereof;

Figure 4 is a side elevation otherwise corresponding to Figure 3, somewhat enlarged; and

Figure 5 is an enlarged section taken along line 5—5 of Figure 1.

I claim:

The ornamental design for a spare tire jacket, substantially as shown.
